US00D908003S

(12) **United States Design Patent** (10) **Patent No.:** **US D908,003 S**
(45) **Date of Patent:** **** Jan. 19, 2021**

(54) **PACKAGING ELEMENT**

(71) Applicant: **RATIONAL PACKAGING LLC**,
Springfield, TN (US)

(72) Inventor: **Samuel C. Voorhees**, Louisville, KY
(US)

(73) Assignee: **RATIONAL PACKAGING LLC**,
Springfield, TN (US)

(**) Term: **15 Years**

(21) Appl. No.: **29/667,161**

(22) Filed: **Oct. 18, 2018**

Related U.S. Application Data

(63) Continuation-in-part of application No. 15/964,439, filed on Apr. 27, 2018, and a continuation-in-part of application No. 29/593,147, filed on Feb. 6, 2017, now Pat. No. Des. 871,908, and a continuation-in-part of application No. 29/593,144, filed on Feb. 6, 2017, now Pat. No. Des. 871,213.

CLAIM

The ornamental design for a packaging element, as shown and described.

DESCRIPTION

FIG. 1 is an upper, right, perspective view of a packaging element, showing my new design;

FIG. 2 is an upper, left perspective view thereof;

FIG. 3 is an upper, rear perspective view thereof;

FIG. 4 is an upper, front perspective view thereof;

FIG. 5 is a left side view thereof;

FIG. 6 is a right side view thereof;

FIG. 7 is a front view thereof;

FIG. 8 is a rear view thereof;

FIG. 9 is a top view thereof; and,

FIG. 10 is a bottom view thereof.
